United States Patent Office

Des. 222,857
Patented Jan. 18, 1972

222,857

INDUSTRIAL VEHICLE

Rigsby C. Satterfield, Chalfont, Pa., assignor to Eaton
Yale & Towne Inc., Cleveland, Ohio

Filed Apr. 3, 1970, Ser. No. 22,232

Term of patent 14 years

Int. Cl. D12—05

U.S. Cl. D14—3

FIG. 1

FIG. 2

FIG. 1 is a front perspective view of my new design for an industrial vehicle;

FIG. 2 is a rear perspective view thereof.

The side opposite to the one shown is a mirror image thereof.

I claim:

The ornamental design for an industrial vehicle, as shown and described.
